UNITED STATES PATENT OFFICE.

SAMUEL LIONEL JEFFERIES, OF SPARTANBURG, SOUTH CAROLINA.

DENTAL MIXING-SLAB.

1,247,406.

Specification of Letters Patent. Patented Nov. 20, 1917.

Application filed April 21, 1917. Serial No. 163,564.

To all whom it may concern:

Be it known that I, SAMUEL LIONEL JEFFERIES, a citizen of the United States, and a resident of Spartanburg, in the county of

5 Spartanburg and State of South Carolina, have invented new and useful Improvements in Dental Mixing-Slabs, of which the following is a specification.

My invention is an improvement in slabs, 10 and has for its object to provide a slab especially designed for mixing plastic material, for use by dentists and the like, wherein the slab is so arranged that it may be used more than once without the necessity of cleaning 15 the slab, the slab being provided with two or more mixing faces.

In the drawings:

Figure 1 is a perspective view of one embodiment of the invention;

20 Fig. 2 is a transverse section;

Fig. 3 is a perspective view of another embodiment of the invention; and

Fig. 4 is a transverse section of the same.

In the embodiment of the invention shown 25 in Fig. 1, the slab 1, which is of glass or other like material, is in the form of a block having an approximately square cross section. Upon each face of the block there is provided a recess 2 formed by cutting away 30 the surface of the block from one face of the block, the said cut away surface being partially inclosed by ribs 3 and 4 at one side and the ends of the face. The reduced or cut away portion provides a mixing face on 35 which the plastic material may be held.

Each face of the block is provided with a cut away portion 2, and it will be obvious that when one face has been used, it is only necessary to cause the block to turn and an-

other face is ready for use. Thus four mixing operations may be performed with the same slab before it is necessary to clean the same.

In the embodiment of the invention shown in Figs. 3 and 4, the slab 5 is in the form of 40 a block of glass or the like, having a rectangular cross section, and the upper and lower faces of the block have the cut away or recessed portions 6 forming mixing faces for the block. Each of these faces is partially 45 inclosed by ribs 7 and 8 at one side and the ends of the slab. With the slab shown in Figs. 3 and 4 two mixing operations may be performed before it is necessary to clean 50 the block.

It will be noticed, from an inspection of 55 Figs. 2 and 4, that all of the cut away portions are similarly arranged, so that as each block is rotated on its long axis the faces will be brought into proper position in succession.

I claim:

1. A slab, comprising a block having a rectangular cross section, and having each face cut away to form a mixing recess, said 65 recesses being similarly arranged and each recess extending to one face of the block throughout the length of the recess.

2. A slab having a plurality of mixing recesses, said recesses being on opposite faces 70 of the slab.

SAMUEL LIONEL JEFFERIES, D. D. S.
